UNITED STATES PATENT OFFICE.

ALEXANDER S. RAMAGE, OF DETROIT, MICHIGAN.

METHOD OF OBTAINING TEMPERATURE CHANGES IN GASES.

1,302,430.

Specification of Letters Patent. Patented Apr. 29, 1919.

Application filed December 3, 1915, Serial No. 64,913. Renewed March 26, 1919. Serial No. 285,385.

To all whom it may concern:

Be it known that I, ALEXANDER S. RAMAGE, a subject of the King of Great Britain, residing at Detroit, in the county 5 of Wayne and State of Michigan, have invented certain new and useful Improvements in Methods of Obtaining Temperature Changes in Gases; and I do hereby declare the following to be a full, clear, and 10 exact description of the same, reference being had to the accompanying drawing, forming part of this specification.

This invention relates generically to a new and improved method of obtaining temperature 15 changes in gases.

It is well known that when it is desired to change the temperature of a gas by expansion or compression, the final temperature T_2 of the gas depends entirely on the initial 20 temperature T_1 multiplied by the constant factor, namely,

$$\sqrt[4]{\frac{p_2}{p_1}}$$

25 in which p_1 is the initial absolute pressure and p_2 is the final absolute pressure. In the production of heat or cold by the compression or expansion of gases it has heretofore been necessary to vacuum insulate the expansion or compression cylinders or use other well known high degrees of insulation, if it is desired to conserve the heat of compression or the cold produced by expansion. The necessity for such high insulations is due to 30 the fact that the factor of radiation increases proportionately with the difference in temperature between the outside air and the gas being compressed or expanded in the cylinder, and thus the greater the difference in 35 temperature the more excessive the factor of radiation. Even when the highest degrees of insulation known are employed, great losses occur in radiation at the time of compression or expansion of the gas, and as a 40 consequence it has been found exceedingly difficult to obtain practically adiabatic results. This will be evident from the fact that, according to the equation

45

$$T_2 = T_1 \times \sqrt[4]{\frac{p_2}{p_1}}$$

50 the final temperature T_2 rises or lowers correspondingly with a rise or lowering of the initial temperature T_1 , and hence, in the case 55 of compression, any loss through radiation

in the initial temperature will have its proportional effect on the final temperature, and, in the case of expansion, a gain in heat units in the initial temperature will serve to increase the number of heat units in the gas 60 at its final temperature.

According to the present invention, the charge of gas undergoing volume change is surrounded by the next succeeding charge to be treated; thus, a heat exchange is effected 65 between the gas undergoing volume change and the next succeeding charge. In the case of compression, the heat units radiated from the gas being compressed are absorbed by the incoming gas or the next succeeding charge 70 to be compressed, thereby raising the initial temperature of that charge with a corresponding increase in the final temperature of the gas. Consequently, if successive charges of the gas are compressed the heat 75 exchange will produce an accumulative rise in the initial temperature of the successive charges before compression, and in this manner practically all the heat of compression 80 is conserved. If the gas is to be expanded, 85 the charge of gas undergoing expansion will absorb heat units radiated from the next succeeding charge to be expanded, thereby bringing down the initial temperature of the next succeeding charge, so that successive expansions result in progressively decreasing 90 initial temperatures of the charges to be expanded. There will, therefore, be a corresponding decrease in the final temperature 95 of the gas.

Whether charges of gas are being compressed or expanded, the difference in temperature between the charge surrounding the compression or expansion cylinder and the outside air is very slight, compared with 95 the difference in temperature between the interior of the cylinder and the outside air. Loss of heat or cold by radiation is consequently not present to an excessive degree, as in former methods, and the problem of 100 insulation is capable of very easy solution.

A preferred form of apparatus for carrying out the improved method of the present invention is illustrated in the accompanying drawings, in which,—

105 Figure 1 is a plan view of an apparatus utilizing the principle of the invention when it is desired to produce cold by expansion, as in the fractional liquefaction or condensation of gases.

Fig. 2 is a plan view of an apparatus designed for the production of heat by the compression of gases.

Reference is now made to Fig. 1 which illustrates an apparatus for carrying out the principle of the present invention, when it is desired to produce cold by the expansion of gases. Within chamber 1 is a coil 2, one end 3 of which communicates, as at 4, with the gas inlet 5. The other end 6 of coil 2 leads out of chamber 1 into a second chamber 7 and directs said gas into a cylinder 8 within chamber 7. The discharge outlet 9 of cylinder 8 communicates with one end of the inner coil 10 of a regenerative coil. The other end of inner coil 10 passes out of chamber 7 into chamber 12 and directs the gas through the inner coil 13 of a second regenerative coil to the inlet 15 of a cylinder 16 within chamber 12. The discharge outlet 17 of cylinder 16 passes out of chamber 12 into the next succeeding chamber 18. Within chamber 18 is an expansion cylinder 19 so mounted as to leave an air space between the outer wall of the expansion cylinder and the inner wall of chamber 18. The expansion cylinder is provided with a piston 20 having a piston rod 21 which drives a crank shaft 22. The gas expanding in cylinder 19 30 may perform external work, and for this purpose crank shaft 22 is provided with a pulley 23 whereby the power produced by expansion may be utilized for any desired purpose. The inlet port 24 and outlet port 25 of the expansion cylinder are controlled by a slide valve 26 mounted on a valve stem 27 conveniently driven by the eccentric 28 on crank shaft 22. The exhaust from cylinder 19 is conducted into chamber 12 by means of an exhaust pipe 29 when the exhaust port 25 of the expanded cylinder is opened by the slide valve 26. From the lower half of chamber 12 the exhaust gas flows into the inlet end 30 of the outer coil 14 of the regenerative coil within chamber 12. Chamber 12 is provided with a separating partition 12^a adjacent the inlet end 30 of said outer coil 14, so as to direct the gas into said outer coil. The gas flows through coil 14 into the outer coil 11 of the regenerative coil within chamber 7 and is discharged through the outlet 31 of said coil 11 into the space beneath the partition 7^a of said chamber. From chamber 7 the exhaust gas passes 55 through outlet pipe 32 surrounding inlet 6 of the incoming gas, back into chamber 1, where it completely surrounds the coil 2 within said chamber 1. All of the chambers are insulated from the outside air, by any ordinary means of insulation, such as felt, mineral wool, or the like, as shown at 35^a.

In all cases of refrigeration of air or gases it is necessary to insert a trap at some point in the system of the apparatus, for freezing out the moisture in the incoming gas before

said gas goes to the expander. If the temperature within chamber 1 is not below freezing the water trap 33 may be located in the outlet 6 of said chamber. Otherwise, the trap must be located farther back in the system, for instance, at the inlet 3 of chamber 1. For this purpose, a second trap 34 may be provided.

In carrying out the method, the gas to be expanded is first compressed and then cooled 75 by any suitable means or apparatus, well understood in the art. The cold compressed gas enters through inlet 3 into coil 2 of chamber 1 wherein the gas is subjected to a preliminary regenerative effect. Circulating 80 through the coil, the gas passes through inlet 6 into cylinder 8 within chamber 7, then out of cylinder 8 through its outlet 9 and flows through the inner coil 10 of the first regenerative coil. The gas next flows 85 through the inner coil 13 of the next regenerative coil, within chamber 12, and through the inlet 15 into cylinder 16. The cold compressed gas passes out of cylinder 16 through outlet 17 into the space within chamber 18 90 surrounding expansion cylinder 19.

Assuming that the inlet port 24 of said expansion cylinder be opened by the valve 26, the first charge of the cold compressed gas enters the cylinder, driving the piston 20 95 against external resistance and doing external work through the medium of the pulley 23 on crank shaft 22. During the expansion of the charge of gas within cylinder 19, the outer wall of the cylinder is entirely surrounded by the next charge of gas to be expanded, so that any inrush of heat units from the next charge to the charge undergoing expansion are subtracted from the temperature of the next charge, thereby lowering 105 its initial temperature.

The result of lowering the initial temperature of successive charges to be expanded may be graphically illustrated by the following: If the initial temperature of the 110 first charge of gas undergoing expansion within cylinder 19 is 60° F. or 521 absolute, and it enters the expansion cylinder at an initial absolute pressure of 150 pounds, then the final absolute temperature of the expanded charge in cylinder 19 is $521 \times .56$, if it be assumed that the charge of gas is expanded to a pressure of 15 pounds. This takes place according to the equation:

$$\begin{aligned} T_2 &= T_1 \times \sqrt[4]{\frac{p_2}{p_1}} \\ &= 521 \times \sqrt[4]{\frac{15}{150}} \\ &= 521 \times \sqrt[4]{.10} \\ &= 521 \times .56 \\ &= 292 \text{ absolute or } -169^\circ \text{ F.} \end{aligned}$$

As stated before, .56 is a constant factor. Therefore, it will be evident that the heat 130

units radiating from the compressed gas surrounding the expansion cylinder and absorbed by the charge of gas undergoing expansion would have the effect of lowering 5 the initial temperature T_1 of the next succeeding charge to be expanded, and consequently the final temperature T_2 of that charge, after expansion, would be much lower than the final temperature of the first 10 charge, after expansion. According to the formula, the temperature of the first charge after expansion would be 521 absolute multiplied by .56, which is equal to 292 absolute or -169° F. The difference in temperature 15 between the first charge after expansion at a temperature of -169° F. and the temperature 60° F. of the charge surrounding the expansion cylinder during the expansion of the first charge is so great that 20 the inrush of heat units from the gas surrounding the expansion cylinder by radiation causes the temperature of the surrounding charge to drop to 500 absolute or 39° F., a difference of 21° F. between its initial 25 temperature and the initial temperature of the charge undergoing expansion. Consequently, the surrounding charge, on being expanded, would drop to a final temperature of 500 absolute multiplied by .56, which 30 equals 280 absolute or -181° F. It will, therefore, be seen that successive expansions of charges of gas within the expansion cylinder will have an accumulative lowering effect 35 on the initial temperature T_1 of each succeeding charge surrounding the expansion cylinder, because of the heat interchange produced at that time. By this the final temperature of the gas in the system can be lowered to a much greater degree than has 40 heretofore been possible, the temperature produced being almost theoretical. The only insulation necessary is to cover chamber 18 and each of the other chambers in the system with felt, or mineral wool, or any 45 other ordinary insulating material.

The cold expanded gas from cylinder 19 passes through outlet pipe 29 into chamber 12, thence through the outer coil of the regenerative coil within said chamber to the outer coil 11 of the regenerative coil within chamber 7, and finally into chamber 1 through outlet pipe 32.

The above described process may be utilized in the fractional liquefaction or condensation of a mixture of two or more gases, such as water gas. In carrying out the process the cold produced in the regenerative coil within chamber 7 would be of such a degree that the carbonic acid gas or carbon dioxid CO_2 would liquefy and collect in cylinder 8 within said chamber 7. The liquefied gas may be drawn off by means of a valve 8^a. The more intense cold in the regenerative coil within chamber 12, would 55 liquefy the carbon monoxid or CO which has

a lower critical temperature than carbon dioxid, the carbon monoxid collecting in cylinder 16 within chamber 12. The liquefied carbon monoxid may be drained off through a valve 16^a. The hydrogen H 70 which has a still lower critical temperature passes out into the expansion cylinder 19. Referring now to Fig. 2 of the drawing: The compressor cylinder 33 is mounted within an insulated chamber 34 in such manner 75 as to leave an air space between the outer wall of said compressor cylinder and the inner wall of the chamber. Within the compressor cylinder is a piston 35 having a piston rod 36 which is driven by a power shaft 37. Atmospheric air or other gas enters the compressor cylinder through the inlet port 40 and is discharged out of the outlet port 41, which outlet port conducts the heated exhaust from the compressor cylinder to any 80 suitable external application. It will be observed that heat units radiating from the charge undergoing compression within the cylinder will be absorbed by the next succeeding charge surrounding the cylinder, 85 thereby raising the initial temperature of the next succeeding charge to be compressed. The heat exchange produces an accumulative effect on the initial temperatures of each succeeding charge to be compressed, it being 90 understood, however, that the initial temperatures of the charges rise, instead of fall, as in the case of expansion in the production of cold.

What is claimed is:—

1. A method of fractionally liquefying gases, which consists in expanding adiabatically successive charges of a mixture of two or more gases, and surrounding the charge undergoing expansion with the next succeeding unexpanded charge and thereby effecting a heat exchange which produces an accumulative lowering effect on the initial temperature of successive unexpanded charges, whereby the temperature of the mixture is 110 reduced by successive stages so as to separately liquefy and recover said gases.

2. A method of fractionally liquefying gases, which consists in expanding adiabatically successive charges of a mixture of two or more gases, and effecting a heat exchange between the charge undergoing expansion and the next succeeding charge to be expanded and thereby producing an accumulative lowering effect on the initial temperature of successive unexpanded charges whereby the temperature of the mixture is 115 reduced by successive stages so as to separately liquefy and recover said gases.

3. A method of fractionally liquefying 125 gases, which consists in compressing and cooling a mixture of two or more gases, then expanding adiabatically successive charges of said mixture, and reducing the temperature of the mixture by successive stages by 130

effecting a heat exchange between each charge undergoing expansion and the next succeeding charge to be expanded, and thereby separately liquefying and recovering said gases.

4. A method of fractionally liquefying gases, which consists in compressing and cooling a mixture of two or more gases, then

expanding adiabatically successive charges of said gases, and reducing the temperature 10 of the mixture by successive stages by surrounding each charge undergoing expansion with the next succeeding charge to be expanded, and thereby separately liquefying and recovering said gases.

ALEXANDER S. RAMAGE.
